BLANK FOR STOCKING FOOT DEVICES

Filed April 22, 1952

FIG. 1.

FIG. 2.

INVENTOR,
WALTER J. PAUL

By Francis D. Ammen

ATTORNEY

UNITED STATES PATENT OFFICE

2,687,583

BLANK FOR STOCKING FOOT DEVICES

Walter J. Paul, Vista, Calif.

Original application March 24, 1951, Serial No. 217,378. Divided and this application April 22, 1952, Serial No. 283,653

2 Claims. (Cl. 36—10)

1

The present application is a division of my pending application titled Blank and Method for Making Stocking Feet, Serial No. 217,378, filed March 24, 1951, and the present invention concerns the blank described in the specification of that application and which is illustrated in the drawing filed therewith.

One of the objects of the present invention is to produce a blank having a form that greatly facilitates the cutting of the blanks from a considerable number of layers of flimsy knit material in one cutting operation; this greatly reduces the cost of manufacture of these articles—stocking feet made from such blanks.

Heretofore, I have manufactured stocking feet of the kind referred to, constructed with a sole seam that extended up to the tip of the toe of the stocking foot. At the point where this toe seam intersected the front-and-rear upper edges of the "vamp" of the stocking foot, it has been necessary heretofore to cut out some of the material there and to provide a short cross-seam in the stocking foot to prevent developing an excess of material at the tip of the toe. The necessity for employing these cross-seams considerably increases the cost of manufacture.

Another object of the present invention is to give an outline for the blank that will enable a stocking foot to be made that will eliminate the necessity for removing the excess material just referred to, at the toe, and which results in giving sufficient material at the tip of the toe to attain a form-fitting effect at this point, in other words, without developing any excess of material there, that is, at the point where the cross seam was formerly located.

Another object of the invention is to provide a blank of symmetrical form and presenting two lobes or extensions located on opposite sides of its axial line, in which the direction in which the lobes extend with respect to said axis facilitates the position of the cutting die that makes the blanks so that the knife when cutting through a succession of layers of stock connected by folded edges, will result in having the lines of knitting in a direction on the lobes that tends to maintain the stocking feet at the size for which they are intended.

Further objects of the invention will appear from a careful reading of the drawing accompanying this application and the description thereof in the following specification.

The invention consists in a blank having the novel features to be described hereinafter, all of which contribute to produce an efficient blank

2

from which to produce stocking feet or stocking foot devices.

A preferred embodiment of the invention is described in the following specification, while the broad scope of the invention is pointed out in the appended claims.

In the drawing:

Figure 1 is a plan view illustrating the preferred form of the blank.

10 Figure 2 is a side elevation of the stocking foot as it would appear when lying substantially flatly upon a surface, and constructed of one of the blanks constituting this invention.

Referring to Figure 1, it will be noted that from 15 the point 9 the upper edges of the blank diverge so as to form a re-entrant angle 9a at this point. This is an obtuse angle approximately slightly less than 180 degrees. By giving this portion of the outline of the blank this form of outline the 20 material at the toe 28 of the completed stocking foot 29 is disposed in such a way that substantially no excess of material will develop when the stocking foot is put on one's foot.

In producing the stocking foot from the blank, 25 the outer edges or sides 8a, of the blank are sewed to form a sole seam 30, the rear portion of which is extended up to merge into the heel seam 31. In doing this, of course, the folded edge 3a and 4a is present as the "vampine" of the stocking foot.

30 The two edges 16a and 16b are formed into narrow hems 16c enveloping the usual slightly elastic cord, not illustrated, the ends of which are located at the point 32.

In the completed article one set of the threads 35 of the material in each side of the completed article should extend in a general longitudinal direction, along the side, that is to say, in a general horizontal direction as viewed in Figure 2. This feature is most advantageous because it reduces the amount of "natural stretch" characteristic of the material and insures that the stocking feet will substantially maintain the size to which they are cut.

Many other embodiments of the invention may 40 be resorted to without departing from the spirit of the invention.

I claim and desire to secure by Letters Patent:

1. A one-piece blank for making a form fitting low cut stocking foot from knit material, said 50 blank having an intermediate toe portion and spaced apart diverging free ends arranged to form the heel portion of the stocking foot when the parts of the blank are assembled to form the stocking foot, said toe portion having a centrally disposed axial line separating the blank into two

uniform and similarly shaped lobes, each of said lobes having an outer side formed with convex edges at its toe and heel portions, the convex edges on each lobe being connected by a concave edge of pronounced regular concavity, the convex edges of the toe portion merging and forming an obtuse re-entrant angle approaching 180°, the vertex of which is on the axial line of the blank so that when the stocking foot is formed there is no excess of material, said lobes having slightly concave inner edges which diverge from a point of origin on said axial line and form an angle of substantially 90° with each other; and the convex outer side of each of the lobes adjacent the free ends having a substantially straight side that intersects the adjacent concave inner edges at an acute angle.

2. A one-piece blank for making a form fitting low cut stocking foot from knit material, said blank having an intermediate toe portion and spaced apart diverging free ends arranged to form the heel portion of the stocking foot when the parts of the blank are assembled to form the stocking foot, said toe portion having a centrally disposed axial line separating the blank into two uniform and similarly shaped lobes, each of said lobes having an outer side formed with convex

10
15

edges at its toe and heel portions, the convex edges on each lobe being connected by a concave edge of pronounced concavity, the convex edges of the toe portion merging and forming an obtuse re-entrant angle approaching 180°, the vertex of which is on the axial line of the blank so that when the stocking foot is formed there is no excess of material, said lobes having slightly concave inner edges which diverge from a point of origin on said axial line and form an angle of substantially 90° with each other; and the convex outer side of each of the lobes adjacent the free ends having a substantially straight edge that intersects the adjacent concave inner sides at an acute angle.
